UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

DUMP-CAR UNDERFRAME.

Application filed April 12, 1926. Serial No. 101,381.

My invention relates to railroad rolling stock and consists in an improved car underframe structure particularly adapted for use on dump cars of the tilting body type. 5 In such cars, it is customary for the car body to be built as a unit and pivotally mounted upon the underframe, the body and the underframe being equipped with hinge-like elements and there being mechanism 10 between the body and underframe whereby the body may be tilted on its hinge elements. Owing to the movement of the car body, the car underframe should not be very wide as it would interfere with the portion of the 15 car body which is lowering in a dumping operation. The car body structure, being movable on the underframe, cannot add any strength or rigidity to the underframe. It follows that the underframe must be made 20 sufficiently compact and strong to accommodate the above conditions, and the underframe, in addition to having the usual duties of carrying the superstructure load and transmitting the buffing and pulling stresses, 25 must resist transverse stresses not usually required of the car underframe but present in cars of this type because of the body tilting mechanism. Such mechanism usually consists of air cylinders with their pistons 30 moving transversely of the underframe, the pistons and cylinders being connected to the underframe and body so that the admission of air to the cylinder thrusts against the car body and underframe and results in tilting movement of the car body.

The object of my invention is to provide an efficient underframe adapted to function as required by the above conditions and preferably my invention consists in a one-piece steel casting of box-shape cross section 40 throughout a substantial portion of its length and having integral hinges or hinge mounting elements, integral brackets for the operating mechanism, integral bolsters, and 45 draft sills, and integral elements for housing or mounting the buffing mechanism which cushions the impact between the tilting body and the underframe.

In the accompanying drawings which illustrate my invention—

Figure 1 is a top view of my underframe.

Figure 2 is a side elevation of the same.

Figure 3 is a transverse section through the underframe along the center line of the 55 bolster and indicating in broken lines the

car truck and car superstructure in two positions.

Figure 3^a is an inclined top view of the buffing mechanism housing provided on the 60 bolster.

Figures 4, 5, 6, and 7 are detail transverse vertical sections taken on lines 4—4, 5—5, 6—6, and 7—7, respectively, of Figure 1.

Figure 8 is a top view of a modified embodiment of my invention.

Figure 9 is in part a side elevation and in part a longitudinal vertical section through the same underframe.

Figure 10 is a detail top view of one of the brackets on the underframe and drawn 70 to a larger scale than shown in Figure 8.

Figure 11 is a transverse section through the underframe illustrating the truck and car body similarly to the showing of the preferred structure in Figure 3.

Figures 12, 13, and 14 are detail transverse sections taken on lines 12—12, 13—13, and 14—14, respectively, of Figure 8.

The preferred underframe structure indicated in Figure 1 includes a box girder center sill 1, and flanged draft sills 3 preferably formed with integral draft lugs 4. The draft sills diverge near their inner ends and the outer ends of the sides of the center sill similarly diverge and these portions then curve or otherwise incline so as to extend transversely of the underframe to merge with or form bolster elements 2. The top and bottom walls of the center sill and the flanges of the draft sills are similarly extended and these features of the underframe 80 greatly increase its resistance to torsional stresses. Two relatively short walls 3^a are substantially aligned with the draft sills and with the sides of the center sill and transfer the longitudinal forces to opposite sides 85 of the bolster.

The outer ends of the bolster are provided with housing members 5 for receiving 100 springs 6 or other mechanism for engaging the car body as the latter is lowered into dumping position. Spaced walls 5^b extend between housings 5 and reinforce these elements against the shocks from the tilting body.

The walls of the center sill structure may be lightened at intervals by suitable openings 7. At intervals the structure has integral upstanding elements 8 upon which the tilting car body may be pivotally mounted.

I show these elements 8 as upward extensions of the top wall of sill 1 and provided with suitable bosses 9 forming extended bearings for the hinge pins 10. As I illustrate the structure, the elements 8 form one of the hinge elements, but, obviously, these elements could consist in pads upon which both hinge elements could be mounted, if desired.

10. Between the bolsters and preferably staggered with the body mounting elements 8 are suitable brackets 11 and 12. These brackets are adapted to mount the air cylinders, air reservoirs, and mechanism connected therewith for tilting the car body. The cylinders and mechanism are not illustrated as different types are now in use and they form no part of my present invention.

One of the operating cylinders or air reservoirs may be mounted on suitable hangers secured to pads 13 on the side and top of the box girder as indicated in Figure 6. Various other modifications of the method of mounting the cylinder on the underframe 25 may be provided.

In connection with the laterally extending brackets 12, I desire also to provide a transverse member 14 (Figure 5) which extends beneath the sill so as to brace the brackets 30 on opposite sides of the sill from each other. The thrust on the underframe produced by the operation of one cylinder may be transmitted not only to the adjacent portion of the underframe but also to the opposite sill 35 or side of the underframe.

In the modification illustrated in Figures 8 to 14 the feature of a one-piece underframe is retained but the same is shown as adapted to mount a dumping body of a different type. 40 and in a somewhat different manner from that indicated in the preferred form. In this modification, the longitudinal members of the underframe consists in two I-shaped sills 15 spaced a substantial distance from each other and connected at intervals by suitable transoms 16. Brackets 17 extend outwardly from sills 15 and form hinge butts for mounting the car body. It will be understood that the corresponding hinge 45 elements on the car body on one side of the underframe may be released to permit the car body to tilt on its hinges on the other side of the underframe.

Each hinge element on the underframe 55 preferably consists of an outer cylindrical portion supported from the side sill by spaced ribs 20, both of which have their inner edges spaced from the web of the side sill 15 and the edge of one of the ribs 60 is cut away a substantially greater distance than the other rib to facilitate molding and casting of the underframe.

As suggested in connection with my preferred embodiment, I contemplate the use 65 of pads on the ends of the brackets 17 upon

which hinge butt elements may be mounted. This is an obvious modification of my invention although I prefer to make use of the integral hinge butts as illustrated.

At the ends of the underframe an end sill 70 18 is formed integrally with the sills 15 and additional longitudinal elements 19 are also formed integrally to provide draft sills.

Various other modifications and changes 75 in the details of the structure described by me may be made without departing from the spirit of my invention and I contemplate the exclusive use of such variations as are included within the scope of my claims. 80

I claim:

1. A car underframe comprising a one-piece casting in the form of a box girder forming a center sill and having integral upstanding elements on which a tilting car 85 body may be mounted.

2. A one-piece casting forming a car underframe longitudinal sill member of box shape cross-section, having upstanding elements on which a tilting car body may be 90 mounted.

3. In a car underframe, a box girder sill member having integral hinge elements on which a tilting car body may be mounted.

4. A one-piece casting forming a box 95 girder car sill with one or more integral elements extending upwardly from the center thereof to form hinge elements for a tilting body.

5. A one-piece casting forming a box 100 girder car sill, the upper wall of which has portions converging upwardly from the sides thereof to form elevated car body mounting elements.

6. A car underframe for a tilting body, 105 comprising a box-shaped girder with integral brackets thereon for mounting mechanism for tilting the car body.

7. In a one-piece casting forming an underframe for a tilting car body, brackets on 110 opposite sides of said underframe for mounting body tilting cylinders or like mechanism.

8. A one-piece casting forming a box-shaped girder underframe adapted to carry 115 a tilting car body and including integral laterally extending brackets for mounting car tilting mechanism.

9. A one-piece casting comprising an underframe for a tilting car body and including integral elements for mounting body carrying hinges and including integral elements for mounting car body tilting mechanism. 120

10. A one-piece casting comprising an underframe for a tilting car body and including integral hinge elements for mounting a car body, and integral elements projecting transversely of the underframe for mounting car body tilting mechanism. 125

11. A one-piece casting comprising a car 130

- underframe of box-shaped cross section and including integral upwardly extending hinge elements for a tilting car body and integral laterally extending brackets for body tilting mechanism.
12. In an underframe for a tilting body car, a sill and members forming pockets for buffing mechanism for the car body, said sill and members being formed integrally with each other.
13. A one-piece casting comprising an underframe for a tilting body car and including a box-shape center sill with bolsters extending transversely thereof and provided with buffer spring pockets.
14. An underframe for tilting car bodies consisting of a one-piece casting comprising a box-shaped girder with integral upwardly facing pockets for body buffing mechanism.
15. In a car underframe, a center sill, a bolster formed integrally therewith, integral elements on said sill for mounting a tilting body hinge, and integral elements on said bolster forming buffer spring pockets.
16. An underframe for a tilting body car comprising a one-piece box girder sill with hinge elements thereon and with a bolster formed integrally therewith and including buffing mechanism pockets located below the top of said sill.
17. In an underframe for tilting body cars, a box-shaped longitudinal sill, integral brackets for body tilting mechanism located on opposite sides of said sill, and a connection between said brackets beneath said sill, all formed integrally.
18. In a car underframe, a center sill, a bolster, the vertical webs of said sill and bolster being inclined to their respective center lines and merging with each other.
19. In a car underframe, a draft sill, a bolster, the vertical webs of said sill and bolster being inclined to their respective center lines and merging with each other.
20. In a car underframe, a box-shaped draft sill, a box-shaped center sill, a bolster between said sills, the vertical front and rear walls of said bolster being curved into said draft and center sills, respectively.
21. In a car underframe, a box-shaped center sill with its sides curving outwardly near its end to extend transversely of the underframe and form a bolster element.
22. In a car underframe, a center sill, a draft sill, the vertical walls of said sills curving outwardly at their adjacent ends to extend transversely of the underframe and cooperating to form the vertical walls of a bolster member.
23. In a car underframe, a center sill having a vertical side wall curving outwardly near its end to extend transversely of the underframe to form a bolster element, and a longitudinal vertical member, for transmitting draft and buffing stresses, substantially aligned with said sill and extending beyond said bolster forming element.
24. In a car underframe, a center sill, a draft sill, said sills having vertical webs curving outwardly at their adjacent ends to form a bolster member, and a relatively short vertical longitudinal member, substantially aligned with said sills, for transmitting longitudinal stresses between them.
25. In a car underframe, spaced draft sills, a bolster, said draft sills diverging near their rear ends and at their ends being inclined outwardly so as to merge with said bolster.
26. In a car underframe, a bolster, and a center sill with its sides diverging near the end of the center sill and at the end extending outwardly to merge with said bolster.
27. A one-piece casting forming a car underframe and including a center sill and a bolster united with each other by vertical arcuate webs.
28. A one-piece casting forming a car underframe and including a draft sill and a bolster united with each other by vertical arcuate webs.
29. A one-piece casting forming a car underframe and including a center sill, a draft sill, a bolster between them, said sills being united with said bolster by vertical arcuate webs.
30. A one-piece casting forming a car underframe and including a center sill, a draft sill, a bolster between them, said sills being united with said bolster by vertical arcuate webs, and integral longitudinal members extending substantially between the adjacent ends of the straight portions of said sills.
31. In an underframe for a tilting body car, a bolster, housings in said bolster for body engaging elements on opposite sides of the center line of said underframe, and reinforcing elements extending between said housings.

In testimony whereof I hereunto affix my signature this 5 day of April, 1926.

WILLIAM M. SHEEHAN.
